UNITED STATES PATENT OFFICE.

HERMANN KRIEG, OF NEUSTADT-ON-THE-HARDT, GERMANY.

STIRRUP.

No. 902,745.

Specification of Letters Patent.

Patented Nov. 3, 1908.

Application filed August 6, 1907. Serial No. 387,313.

To all whom it may concern:

Be it known that I, HERMANN KRIEG, a subject of the German Emperor, residing at Neustadt-on-the-Hardt, Kingdom of Bavaria, Empire of Germany, have invented a new and useful Safety-Stirrup, of which the following is a specification.

My invention relates to improvements in safety stirrups, the object being to provide a stirrup and simple coupling device which will securely hold the stirrup under normal conditions and will readily and automatically release the stirrup the moment these conditions are changed.

In the drawing accompanying and forming part of this specification I have shown in detail certain advantageous forms of embodiment of the invention which, to enable those skilled in the art to practice the same, will be set forth in detail in the following description, while the novelty of the invention will be included in the claims succeeding said description.

Referring to said drawing—Figure 1 is an elevation of a stirrup and coupling especially designed for carrying into effect the objects of this invention, and Fig. 2 is a partial, vertical, longitudinal section.

Corresponding and like parts are referred to in the following description and indicated in the views of the drawings by the same reference characters.

From the usual supporting thong or strap (not shown) is suspended a coupling comprising a substantially straight metal shank A having a small loop a formed on one end for the reception of said strap and on the other end are formed short parallel tongues or hooks a' having beveled ends, as clearly shown in Fig. 2. One face of the shank is recessed, and an arm B, corresponding in dimensions to the recess, is pivoted on a pin C journaled in the shank. On the free end of arm B is formed a single tongue or hook b having beveled ends and adapted to fit and normally lie between the parallel tongues a'. It will, of course, be understood that the same function will be performed by forming two parallel tongues on the arm B and one on the shank A, or one tongue might be formed on the shank and one on the arm, so that the two tongues will lie parallel to each other. Both the shank and arm are recessed above the tongues forming, when the two parts lie together in their normal position, a narrow longitudinal slot D. The arm B is held pressed

against the upper recessed portion of the shank by means of a spring E secured to the shank by screws e e. For the sake of compactness the spring is flat as shown in Fig. 2, 60 and lies flush with one edge of the shank.

The stirrup here shown consists of the usual metal loop G having a flat ribbed or corrugated bottom foot rest g. Substantially midway between the top of the loop and the foot rest 65 is formed a brace bar g' preferably arched on its under side to fit over the instep of the rider. The arch or top of the loop is made somewhat wider than is customary, and a slot g² is so positioned therein with relation to 70 the upper edge of the arch as to form a support or web g³ of substantially the same cross-section as the slot D.

It will readily be understood that in case of an accident the stirrup is moved at an angle to the longitudinal plane of the coupling, the support g³ will be rotated and act as a cam against the two walls of the slot D, rocking the arm B on its pivot and separating the hooks of the shank and arm. The 80 curved edges of the support in their turned position lie on the beveled ends of the hook, and the slightest pull on the stirrup will cause the support to act as a wedge and further spread the hooks, resulting in the ready 85 release of the stirrup. As the bar g' is in close relation to the top of the foot, the slightest movement of the foot out of its normal position will, through the medium of the bar, rock the stirrup and effect its release. 90

I claim—

1. In a device of the character described, a pair of articulated supporting members having overlapping ends and recessed to form a longitudinal slot, in combination with a stirrup having a supporting web of substantially 95 the same dimensions as the slot, whereby the rotation of the web will act as a cam on the articulated members.

2. In a device of the character described, a 100 pair of articulated supporting members having interlocking beveled ends and recessed to form a longitudinal slot, in combination with a stirrup comprising a loop having a slot therein to receive said overlapping ends, and 105 a supporting web above the receiving slot of substantially the same dimensions as the longitudinal slot.

3. In a device of the character described, a 110 pair of articulated supporting members having interlocking beveled ends and recessed above said ends to form a longitudinal slot

between them, in combination with a stirrup having a supporting web rounded on its edges and of substantially the same dimensions as the slot, for the purpose specified.

5. 4. In a device of the character described, a pair of articulated supporting members having beveled hook-shaped interlocking ends and recessed above said ends to form a slot between them, in combination with a stirrup 10 having a supporting web rounded on its edges and of substantially the same dimensions as the slot, and a brace-bar intermediate of the top and bottom of the stirrup.

5. In a device of the character described, a 15 shank having a hook formed on one end, an arm pivoted on the shank having a hook formed on its free end adapted to overlap the

aforesaid hook and provided with a longitudinal recess corresponding to a recess formed in the shank, a flat spring fixed to the shank 20 covering the arm, in combination with a stirrup comprising a loop having a transverse slot therein to receive said hooks, and a supporting web above the transverse slot rounded on its edges and of substantially the 25 same dimensions as the combined recesses, and a transverse brace intermediate of the top and bottom of the stirrup.

In witness whereof I have hereunto set my hand in presence of two witnesses.

HERMANN KRIEG.
